(57) **CLAIM**

The ornamental design for a teething mitt simulative of a duck, as shown and described.

DESCRIPTION

FIG. 1 is a top perspective view of the teething mitt simulative of a duck showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a enlarged, perspective view of detail "9", identified in FIG. 2.

In the drawings, the broken lines depict portions of the teething mitt simulative of a duck that form no part of the claimed
